UNITED STATES PATENT OFFICE.

PETER J. JOECKEN, OF CLEVELAND, OHIO, ASSIGNOR TO THE AMERICAN WASHBOARD COMPANY, OF CLEVELAND, OHIO, A CORPORATION OF OHIO.

WASHBOARD.

SPECIFICATION forming part of Letters Patent No. 694,864, dated March 4, 1902.

Application filed July 17, 1901. Serial No. 68,614. (No model.)

To all whom it may concern:

Be it known that I, PETER J. JOECKEN, a citizen of the United States, residing at Cleveland, in the county of Cuyahoga and State of Ohio, have invented or discovered certain new and useful Improvements in Washboards, of which improvements the following is a specification.

The invention described herein relates to certain improvements in washboards, and has for its object a construction of a washboard-frame whereby suitable cushions or yielding portions are formed to support the rubbing-face in position, thereby rendering it possible to employ a rubbing-face formed of a frangible material, as clay or glass.

The invention is hereinafter more fully described and claimed.

In the accompanying drawings, forming a part of this specification, Figure 1 is a perspective view of a washboard embodying my improvement. Fig. 2 is a sectional elevation of the same; and Fig. 3 is a transverse section on a plane indicated by the line III III, Fig. 2.

In the practice of my invention the washboard is formed, as is customary, by the legs 1, the upper and lower cross-pieces 2 and 3, headpiece 4, and brand-board 5, said parts being constructed and connected together in the usual or any suitable manner, except in so far as may be hereinafter stated. The inner walls or sides of the legs and cross-bars are grooved or recessed for the reception of the edges of the rubbing-face 6, which may be formed of glass, clay, or other suitable material. When formed of clay or other porous material, the surface is coated with a vitrified material, so as to form a smooth even rubbing-surface. The bearing walls of the recesses in the frame are made yielding or resilient, so as to yieldingly support the rubbing-face. This may be done in a variety of ways—as, for example, narrow grooves or saw-kerfs are formed or cut in the frame closely

adjacent to the recesses, thereby forming thin walls or ribs 7 7^a of wood adjacent to the rubbing-face and integral with the frame. These ribs are made sufficiently thin so as to be capable of yielding or forming cushions on the 50 sides of the rubbing-face, so as to prevent injury to the latter when in use, and also to permit of a certain amount of warping or twisting of the legs without injury to the frangible rubbing-face. It will be observed 55 that the ribs 7 along the front of the rubbing-face extend a considerable distance beyond the upper and lower ends of the rubbing-face and that in forming the sockets in the legs for the reception of the ends of the cross-bars 60 the ribs 7 a in the rear of the rubbing-face are cut through, so that said ribs 7 7^a will yield readily to lateral pressure or impact.

The front rib or cushion 9 in the cross-bars is preferably formed by recessing the 65 cross-bars for the reception of the upper and lower edges of the rubbing-face in close proximity to their front edges, so as to produce a yielding or resilient rib or front wall, as shown in Fig. 3.

I claim herein as my invention—

1. A washboard having in combination a frangible rubbing-face, a main frame having recesses for the reception of the edges of the rubbing-face, said recesses having resilient 75 bearing-walls, substantially as set forth.

2. A washboard having in combination a frangible rubbing-face, a main frame having recesses for the reception of the edges of the rubbing-face, the bearing-walls of the grooves 80 being formed by resilient ribs integral with the corresponding part of the main frame, substantially as set forth.

In testimony whereof I have hereunto set my hand.

PETER J. JOECKEN.
